UNITED STATES PATENT OFFICE.

CURT PINKERT, OF DRESDEN, GERMANY.

SCREW PROPELLER.

Application filed July 19, 1922. Serial No. 576,109.

To all whom it may concern:

Be it known that I, CURT PINKERT, a citizen of the Republic of Germany, and resident of Dresden, Saxony, Germany, have invented certain new and useful Improvements in Screw Propellers, of which the following is a full, clear, and exact specification, reference being had therein to the accompanying drawings.

- 10 In air and water propellers the theoretically correct clean screw surface loses a considerable amount of its efficiency as a result of incidental influences. Attempts have been made to remedy this by reducing the pitch from the hub as the circumference is approached, but fully satisfactory results have not yet been obtained. The invention is based upon the recognition of the fact that apart from the various large circumferential ways on the various radii the varying great circumferential velocities pertaining to same must be taken into consideration, so that despite the difference of these velocities a discharge of water, as uniform as possible, takes place from the point to the hub. For this purpose according to the invention the pitches are so reduced as the circumference is approached, that in the vicinity of the circumference the parts of 20 the blade which there move more quickly against the water have lower pitches, not only in accordance to the greater distance covered but also in accordance to the greater shock when striking the water, due to the 25 higher speed, whereas as the hub is approached the opposite conditions prevail for the same reason. As a practical measure for properly determining the pitch in this case the division of the radius of the propeller 30 into an uneven number of parts, preferably five, is expedient, whereby the circumference of the hub lies on the innermost fifth of same and the middle pitch on the third fifth.
- 35 The amount of pitch reduction is an essential part of the invention, as explained below from a number of examples.

The drawing shows a plan of the new propeller, whereby several applications are 40 considered.

Fig. 1 is a circular diagram showing the fundamental circles for setting in the various pitches and the blade forms.

Figs. 2 to 5 are pitch diagrams from which

the essential kinds of pitch-increase as the hub is approached will be readily seen.

Fig. 6 is the diagram of a water passage to a propeller according to Fig. 5.

The radius is divided into five parts in such manner that five circumferential circles, 1, 2, 3, 4, 5, Fig. 1 at equal distances from each other are produced. The inside circle 1 is at the same time the hub circumference.

According to the first application (Fig. 65 2) the pitch 5, the lowest on the circumference, has been taken as base and the further pitches s^4 , s^3 , s^2 , s^1 , have in each event been enlarged a fifth of the pitch s^5 .

According to the second application (Fig. 70 3) the middle pitch s^3 has been taken as base and from here, as the circumference is approached the pitches s^4 and s^5 have each time been reduced a fifth and as the hub is approached, the pitches s^2 and s^1 each increased a fifth.

According to the third application (Fig. 4) the point of departure has in turn been taken from the smallest pitch on the circumference in such manner that the next 80 pitch s^4 is a fifth larger than s^5 , the next pitch s^3 also another fifth larger than s^4 and so on.

According to the fourth application (Fig. 5) the middle pitch s^3 on the third circle has 85 been taken as point of departure. The formulas for the entire series of pitches on the five radii are as follows:

$$\begin{aligned} \text{Pitch } s^1 &= s^5 : 0.6 \\ \text{Pitch } s^2 &= s^5 : 0.8 \\ \text{Pitch } s^3 &= s^5 : 1.0 \\ \text{Pitch } s^4 &= s^5 : 1.2 \\ \text{Pitch } s^5 &= s^5 : 1.4 \end{aligned}$$

The hub pitch is accordingly in this increase of pitches which is similar to a tangent curve more than double the pitch at the circumference.

This calculation is based on the following:

Figure 6 shows in simplified diagram 100 form the water passage through the propeller blades. The relative movement of the liquid with respect to the screw takes place for each blade element on the radius r^1 , r^2 , r^3 , r^4 and in corresponding planes which 105 may be imagined as placed one over the other. The liquid which approaches the screw axially with the velocity at an end-

less distance from the screw, undergoes, in passing through, a change of velocity as well as of direction from ae^1 , ae^2 to ae^1 , ae^2 , etc. In this way from 1, 2, 3, etc. circumferential velocity of the respective screw element is developed at the same time in a plane perpendicular to the axle. The lines e^1 , b^1 , e^2 , b^2 , etc. show the velocity of the water discharge with respect to the screw-bearer. The figure shows plainly how these are set in the same direction, whereas in the case of non-varying pitch the directions diverge considerably.

On the assumption that the relative discharge velocities with respect to the screw-bearer are set in the same direction and become equally high, the following law must be valid, which can also be deduced readily from Fig. 6:

$$20 \quad \frac{z_1}{z_1+v} = \frac{2z_2}{z_2+v} = \frac{3z_3}{z_3+v} = \frac{4z_4}{z_4+v} = \frac{5z_5}{z_5+v}$$

or

$$25 \quad \frac{1}{1+\frac{v}{z_1}} = \frac{2}{1+\frac{v}{z_2}} = \frac{3}{1+\frac{v}{z_3}} = \frac{4}{1+\frac{v}{z_4}} = \frac{5}{1+\frac{v}{z_5}}$$

If in a model propeller $v=100$ mm. per second and one revolution, and $z_1=100$ as well, the constant $=\frac{1}{2}$ and the total pitches become as follows:

$$r = \frac{R}{5} \quad s^1 = 200 \quad \text{Mm.}$$

$$r = \frac{2R}{5} \quad s^2 = 133.3$$

$$r = \frac{3R}{5} \quad s^3 = 120$$

$$r = \frac{4R}{5} \quad s^4 = 114.3$$

$$r = 5R \quad s^5 = 111.1$$

or for:

$$r = \frac{R}{5} \quad s_1 = s_5 : 0.6 = 200$$

$$r = \frac{2R}{5} \quad s_2 = s_5 : 0.9 = 133.3$$

$$r = \frac{3R}{5} \quad s_3 = s_5 : 1.0 = 120$$

$$r = \frac{4R}{5} \quad s_4 = s_5 : 1.05 = 114.3$$

$$r = \frac{5R}{5} \quad s_5 = s_5 : 1.08 = 111.1$$

55 A large number of tests showed, however, that this purely theoretical consideration, without taking into count the resistances met at the time, does not give satisfactory results, but that on the contrary a contortion of the curve around its center must take place in a certain sense, in order to overcome the resistance which appears in particular at the end of the hub. As the contortion on the hub-stem of the curve must be greater, in order to turn aside the

velocity of the water discharge toward the middle more than at the end, the final law of pitch may be best expressed as follows:

$$\begin{aligned} \text{Pitch } s_1 &= s_5 : 0.5 \\ s_2 &= s_5 : 0.85 \\ s_3 &= s_5 : 1.0 \\ s_4 &= s_5 : 1.06 \\ s_5 &= s_5 : 1.1 \end{aligned}$$

70

The outlines of the blade are optional, 75 but in addition to a pitch favorable to the working of a propeller, the best shape of blade is also necessary, which as the result of tedious and expensive tests has been found to be as follows:

The circular screw surface is according to Fig. 1 subdivided for this purpose, that is the sharp definition of the propeller outline by 10 concentric circles of the same annular width. Circle 1 is the nominal circle. In like manner radii are drawn symmetrically to center 2 at an angle of 60° to the middle of the blade and the sixths of the surface of the circles are divided up in 8 similar parts = 7.5° circular measure.

85

90

The projected surface of each screw propeller is now determined as follows:

1. Entering and emerging edges form a radius in running toward the hub.

2. The outline is further determined by the points where the centric circles cross the radii. Compare surface I and surfaces II and III for twin screw steamers and the surfaces IV and V for single screw steamers, the surface outlines of which, however, may be varied still more in the same sense.

95

3. According to the charge and use of the propeller, as twin or single screw steamer, the entire surface within the third section of circle is divided up.

100

Having now more fully described and ascertained the nature of my invention and in what manner the same is to be performed, I declare that what I claim is:

1. Screw propeller comprising a hub and blades with a pitch decreasing from the hub to the periphery, the largest radius being divided in equally stepped radii, a main pitch being provided on a certain radius on the other radii lying towards the hub the pitches each being enlarged successively by the quotient of the main pitch divided by their number of radii.

110

2. Screw propeller comprising a hub and blades with a pitch decreasing from the hub to the periphery, the largest radius being divided in equally stepped radii, a main pitch being provided on a certain radius, on the other radii lying towards the periphery the pitches each being decreased successively by the quotient of the main pitch divided by the number of radii.

115

3. Screw propeller comprising a hub and blades with a pitch decreasing from the hub to the periphery, the largest radius being

125

130

divided in equally stepped radii, a main pitch being provided on a certain radius, on the other radii lying towards the hub every pitch being enlarged by the quotient of the foregoing pitch divided by the number of radii.

4. Screw propeller comprising hub and blades with a pitch decreasing from the hub to the periphery, the largest radius being divided in equally stepped radii, a main pitch being provided on a certain radius, on the other radii every successive pitch being as great as the quotient of the product of the main pitch and number of radii divided 10 by numbers successively decreasing by one unit towards the hub.

5. Screw propeller comprising a hub and blades with a pitch decreasing from the hub to the periphery, the largest radius being divided in equally stepped radii, a main pitch being provided on radius near to the 20 middle of the length of the blade, on the

other radii every successive pitch being essentially as great as the quotient of the product of the main pitch and number of radii divided by a number, which on the main pitch radius is equal to the number of radii, whilst it decreases towards the hub successively by one unit, and is enlarged towards the periphery successively by one 25 unit.

6. Screw propeller comprising a hub and blades with a pitch decreasing from the hub to the periphery, (in accordance with claim 5), the axial view of the blade being substantially confined up to the middle of the length of the blade by radial edges up to the maximum blade width, whilst in the external part the blade is confined by spiral edge lines, drawn through the crossing 35 points of equally distributed radii and equally distributed peripheral circles.

In witness whereof I affix my signature.
CURT PINKERT.
